United States Patent Office

Des. 209,112
Patented Oct. 31, 1967

209,112

BATTERY OPERATED WRITING INSTRUMENT OR THE LIKE

Herbert A. Plassmann and Fred H. Searls, Bryan, Ohio,
assignors, by mesne assignments, to Bernard S. Benson,
Dordogne, France

Filed Aug. 15, 1966, Ser. No. 3,470

Term of patent 14 years

(Cl. D74—17)

FIG. 1

FIG. 2

FIG. 3

FIG. 4

FIG. 5

FIGURE 1 is a front elevational view of a battery operated writing instrument showing our new design, the undisclosed back being a mirror image thereof;

FIGURE 2 is a top plan view;

FIGURE 3 is a bottom plan view;

FIGURE 4 is a right side elevational view; and

FIGURE 5 is a left side elevational view thereof.

We claim:

The ornamental design for a battery operated writing instrument or the like, substantially as shown and described.
